SPEED CHANGING AND COUPLING
DEVICE

Emil Ley, Muttenz, near Basel, Switzerland

Application October 29, 1932, Serial No. 640,283
In Switzerland October 30, 1931

1 Claim. (Cl. 192—61)

The present invention relates to a hydraulic speed changing and coupling device of the kind wherein the rotating driving element is provided with a drum containing a liquid body affecting, 5 upon rotation of the drum, a ring like form, whilst the drum encloses liquid feeding rotary gears which are in operative relation with the element to be driven and the purpose of which is to establish a circulation of the liquid, these liquid 10 feeding rotary gears being located within an inner housing and being controlled in such a way by a controlling mechanism on the latter capable to throttle or not the circulation of the liquid so as to transmit, or not, the driving motion of the 15 driving element to the element to be driven.

The invention concerns a particular form of said controlling mechanism. According to this invention, the controlling mechanism comprises for each liquid feeding gear two liquid channels within 20 in said housing, one for the admission of liquid to and the other for the delivery of liquid from said gear, having their inner openings within the same transverse plane, but their outer openings axially displaced to one another on the outer 25 periphery of said housing, in combination with an axially slidable controlling valve on the outer periphery of said housing, arranged so as to throttle more or less the liquid delivery channel, whilst keeping the admission channel permanently open, and having the form of a housing enclosing cup with end openings for allowing axial circulation of liquid around said valve.

In order that the invention may be more fully understood, there will now be described, by way 35 of example, and with reference to the accompanying drawing a preferred embodiment of the invention.

Figure 1 is a partial longitudinal section through the device;

Figure 2 is a corresponding transverse section according to line A—B of Figure 1, and

Figure 3 is a top view of a certain part of the device.

a designates the rotating driving shaft and b 45 designates the rotating driven shaft. Securely mounted on the shaft a is a drum c made of two pieces. The drum a contains a liquid, for instance oil, which, upon rotation of the drum, forms a ring on the inner wall of the latter by virtue of the centrifugal force. Provided in the drum c is a circular member d, having in the 50 present case three cavities e, for instance which are uniformly distributed about the rotating axis of the device. In each of the cavities d there is a toothed liquid feeding gear f, which is rotatably

mounted in the oppositely situated walls of the member d. Each of the cavities e is in open communication with two channels g, h, having their inner openings within the same transverse plane and terminating at different points of the periphery of the member d. The channel g serves for the admission and the channel h for the delivery of liquid, which during operation of the device flows out of the circular liquid body in the drum c, by rotation of the feeding gear f about its own axis in a direction indicated by the arrow x through the channel g to the gear f, which feeds it along its periphery to the channel h, where the liquid will join again the circular liquid body.

The outer openings g¹ of the oil admission channels g of the three cavities e are uniformly distributed on the periphery of the member d within one and the same transverse plane; in a similar manner, the openings h¹ of the delivery channels h of the three cavities e are also uniformly distributed on the periphery of the member d, but they are arranged in a transverse plane which is axially displaced with respect to the plane mentioned before. Whilst the openings g¹ of the admission channels g are constantly open, the openings h¹ of the delivery channels h can be partly or entirely closed. To this end, there is provided a circular controlling valve i on the periphery of the member d, this valve being slid- 80 able in the axial direction and adjustable in position by means of a controlling lever k which is connected to a sleeve l provided on the valve i and extending laterally out of the drum c, as shown in Figure 1. The oil feeding gears f are in engagement by their teeth with a common toothed wheel m, which is keyed on the shaft b to be driven. The sliding valve i has the form of a cup with openings i² in its bottom for allowing axial circulation of liquid around the valve, which may be 85 of some advantage for cooling purposes.

The operation of the above described device is as follows:

In the illustrated position of the valve i, the openings h¹ of the delivery channels h are entirely open.

When the drum c is rotated by the shaft a, the liquid in the drum c will assume the form of a ring o, which will cover the openings g¹, h¹, provided, of course, that there is a sufficiently large quantity of liquid in the drum c, whilst the feeding gears f, which rotate as planetary elements around the axis of rotation of the drum, by their rolling off on the common toothed wheel m, will continuously shift a certain quantity of liquid 110

through the corresponding channels g, h from one place to another. The toothed wheel m and the shaft b are at rest, which means that the device is in its running light or no-load condition. If now the valve i is shifted in such a manner that it will cover more or less the openings h^1 of the delivery channels h , the circulation of the liquid through the channels g, h will be more or less throttled. As a result thereof, the rotation of the feeding gears f about their own axis will be braked at a corresponding rate, and inasmuch as these planetary gears f continue to rotate with the drum c , they will exert a corresponding torque upon the toothed wheel m , so that the latter will be rotated with a peripheral speed corresponding to the throttling rate of the liquid circulation, this peripheral speed being for the moment still smaller than the rotating speed of the driving shaft a , so that the driving movement of the shaft a will be transmitted at a certain speed changing rate to the shaft b .

When finally the valve i is shifted so far that it will entirely cover the openings h^1 of the delivery channels h , the circulation of the liquid in the feeding gears f is completely stopped, so that the latter no longer rotate about their own axis. The gears f now drive the toothed wheel m together with the shaft b in the same way as a coupling, with a rotating speed which nearly corresponds to the rotating speed of the shaft a . The device is in a direct drive condition.

It is clearly evident, from the foregoing, that by displacement of the controlling valve i any desired speed changing rate between the driving shaft and the shaft to be driven can be obtained, the rotating speed of the driving shaft being thus transmitted to the shaft to be driven in a smooth continuous way and not by steps.

Instead of the three liquid feeding gears only

40

80

one or two, or more than three could be provided in the device. The toothed feeding gears can also be replaced by other rotating feeding gears, for instance by winged gears or the like.

The liquid which may be heated on its circulation in the drum c , may cool down on the rotating peripheral wall of the latter exposed to the outer air. The drum could, of course, be provided with cooling ribs or with special cooling means.

The described device may also advantageously be used as a simple coupling to be combined with the usual speed change gear in auto-cars.

What I claim is:—

In a hydraulic speed changing and coupling device of the kind comprising a driving element, a driven element, a liquid containing drum fixed to the driving element, a housing within said drum, arranged so as to dip into the ring of liquid formed within the drum when being rotated, at least one liquid feeding rotary gear located in said housing and having a cooperating toothed member, fixed to the driven element, a mechanism for controlling the flow of liquid through said liquid feeding gear, comprising two liquid channels within said housing, one for the admission of liquid to and the other for the delivery of liquid from said gear, having their inner openings within the same transverse plane, but their outer openings axially displaced to one another on the outer periphery of said housing, in combination with an axially slidable controlling valve on the outer periphery of said housing, arranged so as to throttle more or less the liquid delivery channel, whilst keeping the admission channel permanently open, and having the form of a housing enclosing cup with end openings for allowing axial circulation of liquid around said valve.

EMIL LEY.
